UNITED STATES PATENT OFFICE.

GEORGE F. EGAN, OF JERSEY CITY, NEW JERSEY.

DISPLAY DEVICE.

Original application filed August 3, 1925, Serial No. 47,865. Divided and this application filed April 8, 1926. Serial No. 100,617.

The present invention relates to improvements in display devices and constitutes a division of my copending similarly entitled application, filed August 3, 1925, Serial No. 47,865.

An object of the invention described and claimed herein is to provide a simple, inexpensive, but rigid and durable, holding device for cards, tags and the like employed for the purpose of displaying the price, stock numbers or other information in connection with goods placed upon shelves or other similar supports.

The invention has for a further object to provide an unobtrusive, neat and compact device which may be securely held upon the shelf or support, or placed on a flat surface, and which will support a card.

With the foregoing and other objects in view, the invention will be more fully described hereinafter, and will be more particularly pointed out in the claims appended hereto.

In the drawings, wherein like symbols refer to like or corresponding parts throughout the several views;

Figure 1 is a perspective view showing a device constructed according to the present invention;

Figure 2 is a front elevation of the same showing a card in place therein;

Figure 3 is an edge view thereof; and

Figure 4 is a vertical section taken on the line 4-4 in Figure 2.

Referring more particularly to the drawings, a shelf is represented by dotted lines at 53 in Figure 1. The flange members 54 and 55 are shown as engaging the upper and lower walls of the shelf, and a V-shaped panel 56 is shown as extending upwardly from the lower clamp member 54. This partial panel 56 may rest against the front wall of the shelf when the device is in position on the shelf. Side strips 57 and 58 are shown as connecting the lower and upper clamp members at the ends of the device, and a horizontal strip 59 is shown as extending between the strips 57 and 58. A slot 60 is shown as provided for the insertion of a

card 61. A card inserted in the slot 60 will be held in place by the strips 57 and 58 and the partial panel 56, the strips 57 and 58 preventing the card from falling frontward, and the partial panel 56 preventing the card from falling backward.

The downward movement of the card is checked at the points where the side strips 57 and 58 and the clamp member 54 merge.

In the use of the device a card showing a price designation is indicated in Figure 2, the ends of this card being indicated in dotted lines. The card is shown as of a length to admit of its being passed through the slot 60 at the top of the device, but the strips 57 and 58 overlap the end portions of the slot 60, so that the ends of the price card are shown as confined by such strips, the strips extending in front of the card, while the V-shaped panel 56 lies in back of the card. In other words, as shown in Figures 3 and 4, the partial panel 56 is in a plane offset behind the plane in which the strips 57 and 58 lie.

It is obvious that various changes and modifications may be made in the details of construction and design of the above specifically described embodiment of this invention without departing from the spirit thereof.

What is claimed is:

1. A display device comprising upper and lower clamping members adapted to fit the upper and lower walls of a shelf, a partial panel extending upwardly from the lower clamping member and adapted to lie against the front wall or edge of the shelf, strips extending between the upper and lower clamp members at the ends of the device and lying in a plane offset outwardly from the plane of said partial panel, a horizontal strip extending across between said end strips at the upper portions of the latter, said upper clamp member and horizontal strip having a slot therebetween for receiving a card, said slot being disposed in a plane between the planes of the strips and partial panel, the ends of said slot overlapping the end strips.
2. A display device comprising means to

support the device, a partial panel extending upwardly from the lower portion of said means, strips extending between the upper and lower portions of said means at the ends 5 of the device and lying in a plane offset outwardly from the plane of said partial panel, a horizontal strip extending across between

said end strips at the upper portions of the latter, said device having a slot adjoining the horizontal strip for receiving a card, 10 said slot being disposed in a plane between the planes of the strips and partial panel.

In testimony whereof I affix my signature.

GEORGE F. EGAN.
